(57) **CLAIM**

I claim the ornamental design for a glove, as shown and described.

DESCRIPTION

FIG. 1 is a back elevational view of one embodiment of a glove of the present invention;

FIG. 2 is a front elevational view of the glove of FIG. 1;

FIG. 3 is a first side elevational view of the glove of FIG. 1; FIG. 4 is a second side elevational view of the glove of FIG. 1; and,

FIG. 5 is a top plan view of the glove of FIG. 1.

The broken lines shown in the drawings illustrate features of the article to which the design is applied that form no part of the claim.
